REGENERATIVE REPEATING SYSTEM

Louis M. Potts, Evanston, Ill., assignor to Teletype Corporation, Chicago, Ill., a corporation of Delaware

Application November 9, 1942, Serial No. 464,993

12 Claims. (Cl. 178—70)

This invention relates to signal repeaters and particularly to a repeater for regenerating signals in which the final impulse of a permutation code combination also acts as a special control impulse.

The primary object of the present invention is to provide a repeater for start-stop systems of automatic telegraphy in which the rate of transmission is increased or the line frequency is decreased by utilizing the character of the last 10 character signal impulse for a dual purpose.

Another object of the present invention is to provide a simple regenerative repeating apparatus for repeating signals of the start-stop variety having no separate impulse allotted for a stop impulse.

The manner of signaling employed in connection with the present invention is exemplified by the system shown in co-pending application Serial No. 334,108, filed May 9, 1940, now Patent No. 2,323,932, granted July 13, 1943, by L. M. Potts, in which there is employed a five-unit Baudot-type code combination signal having, in addition to the conventional five selective impulses, a special impulse utilized for supervising secondary shift control at a start impulse interval of a polarity opposite to that of the preceding impulse interval. The device according to the present invention is based on the regenerative repeater shown in U. S. Patent No. 2,104,251, and provided with an additional cam adapted to operate the stop lever at the end of a revolution of the shaft so that the stop lever will be invariably held in the stop position at the end of a signal interval regardless of the position of the armature of the magnet in the repeater at the end of the cycle. The armature of the regenerative repeater has an extra movable contact which moves between a pair of fixed contacts which are, in turn, connected, under control of the distributor shaft in the repeater, to ground when the distributor shaft is in the stop position. Upon receipt of an impulse by the repeater from the transmitting station, which is the reverse of the last or the fifth impulse previously received, the repeater will initiate repeating operations to carry the impulses received by it, in the transmission of the code combination, forward to the receiving station and thereby serve the normal purpose of a regenerative repeater. Of course, the repeater will correct the duration of impulse and the strength thereof in the well known manner. Therefore, the salient purpose of the present arrangement is to shorten the code combination so that the same fundamental signal frequency will

give a higher rate in words per minute, or the same rate in words per minute will give a lower fundamental signal frequency.

For a more comprehensive understanding of the present invention, reference may be had to the accompanying drawing and to the detailed specification following hereinafter in which similar reference characters indicate corresponding parts throughout, and in which:

Fig. 1 is a schematic diagram of the repeater system according to the present invention in which the signals are of conventional length, but in which a sixth impulse is incorporated with the stop interval and the start impulse is varied to contrast with the stop impulse;

Fig. 2 is a diagrammatic chart of a code signal such as may be used in the system disclosed in Fig. 1, showing how its component parts are functionally allocated; and

Fig. 3 is a side elevational view of the stop gate control mechanism.

Referring to Fig. 1, line wire 1 connects a transmitting substation indicated generally as 2, and a repeating station 3 comprising a signal receiving magnet 4 in a controlling circuit. Repeating means is positioned between magnet 4 and a receiving station 5, and line wire 6 connects the repeating station with the receiving station.

Whereas conventional five-unit permutation code signals being provided with seven componential impulse intervals contemplate start and stop impulses of predetermined and invariable current characteristics, means are herewith provided for varying the characteristic of the stop signal interval so that it may have utility for selection as well as phasing supervision and for making the start initiating apparatus responsive to a start impulse condition of electrical polarity opposite to that of the immediately preceding stop impulse interval which may consist of either one of two alternative current conditions.

In the incorporation of this plan of operation, it has been found expedient to utilize plus and minus current conditions to represent marking and spacing, instead of the conventional practice of utilizing current and no current conditions for this purpose. Moreover, there will be utilized for the purpose of signal translation, a six-feeler testing apparatus generally indicated by the reference character 7. Feeler mechanism 7 is illustrated as having seven contactors 8 to 14, inclusive; however, contactors 13 and 14 are both carried upon a single feeler lever while each of

the remaining contactors 8 to 12, inclusive, is carried individually upon a feeler lever.

In accordance with the operation of its feeler lever, each contactor is spring urged so that it will engage the contact block toward the right (as viewed in Fig. 1) and is capable of movement in an opposite direction so as to engage the contact block towards the left, as illustrated in Fig. 1. The contact block at the right is comprised of a large section indicated 15, and a smaller section, insulated therefrom, indicated 16. The contact block at the left is similarly comprised of two sections, the larger one indicated 17, and the smaller one indicated 18. Moreover, as may be noted, the small contact block 18 is connected electrically over an obvious line with the large block 15, and correspondingly, small contact block 16 is connected electrically with the large contact block 17. Opposite sources of grounded battery or potential indicated 19 and 21 are connected, respectively, to the contact blocks 18 and 16 and over lines 22 and 23 to the oppositely placed contact points of armature 24 under the control of a polar relay 25.

One terminal of relay 25 is connected to the afore-described contactor 14 and the other to a distributor segment 26, located in the distributor ring 27. The distributor 28 which includes, also, distributor rings 29, 31, and 32 is of the start-stop type having a brush carrier 33, which supports two pairs of bridging wipers or brushes 34 and 35. Brush carrier 33 of transmitting distributor 28, is conventionally illustrated in Fig. 1, but it is to be understood that this element is driven through a friction coupling, preferably in a rotary direction that it may be restrained from movement by the intervention of an armature 36 under the control of a start magnet 37. Also, the pair of wipers 34 serve to connect segmented distributor ring 29 with the solid distributor ring 31 which is electrically connected to the line conductor 1; and that the pair of wipers 35 correspondingly connect distributor ring 27 which contains the segment 26 previously described, with the grounded distributor ring 32.

Reference will now be had to distributor ring 29 which, as will be seen in Fig. 1, is made up of seven segments. When the brush carrier 28 is in its arrested position, wiper 34 is contacting the slightly longer segment designated 5 in the distributor ring 29. Also, it may be observed that following the segment 5, which serves also in the capacity of a stop segment as will be later described, there is encountered a start segment designated by the character S.

Following this segment is a segment designated 0 (zero), which has been arbitrarily assigned to the function of controlling the secondary shift which is fully described in co-pending application Serial No. 334,108 previously mentioned. This control is otherwise executed, in accordance with the present embodiment in a manner generally similar to that described in connection with the disclosure of said co-pending application. The remaining segments 1, 2, 3, etc., including segment 5 (which, as has already been stated, functions in a dual capacity), serve to distribute those signal impulses which relate to the composition of the permutation code. Segment 5 is connected over a conductor 38 to the contactor 13. Segment S is connected over a conductor 39 to the armature 24 of polar relay 25. In Fig. 1 is illustrated diagrammatically, transmitting station equipment including a perforated tape controlled mechanism and a rotary

signal transmitter under the supervision thereof for issuing signals of a type adapted to exercise the control function including primary and secondary shift supervision of printing apparatus 5 having mechanically the characteristics exemplified in the showing of Fig. 11 of the co-pending application, Serial No. 334,108 which is diagrammatically shown in the box portion 5 of Fig. 1 of the present disclosure.

- 10 As the brush carrier 33 proceeds in the downward direction as indicated by the arrow 40, the pair of wipers 34 leave segment No. 5 and encounter segment S, bridging this element of distributor ring 29 with the solid ring 31. Assuming for the sake of illustration, that the perforated tape signal which has just been positioned and which has been impressed upon the feeler levers of record reader 7 is such that contactors 13 and 14 (which operate in unison) 15 are moved to the right, that is to say, with contactor 13 engaging block 15, and contactor 14 engaging block 16, distributor segment No. 5 will have received positive current potential from grounded battery 19 over conductor 38. This circuit is traceable from positive battery 19, segment 18 to segment 15, contactor 13, conductor 38, segment No. 5 of distributor ring 29, brushes 34 to outgoing conductor segment or ring 31 which is grounded at the repeating station 3. As 20 the brushes proceed to the next segment which is designated S, opposite polarity is issued from grounded battery 21 as polar relay 25, in accordance with its preceding operation, has been left in a position whereat its armature 24 engaged 25 the contactor of conductor 23. This circuit is traceable from negative battery 21, conductor 23, armature 24, conductor 39, segment S of distributor ring 29, brushes 34 to line ring 31.
- If instead of the supposed example described 40 above, the particular signal had been one in which the feeler lever with which contactors 13 and 14 are integrally associated was positioned to the left causing engagement with contact block 17 and 18 instead of contact block 15 and 16, the 45 electrical characteristics relative to segment 5 and S would be opposite to that just described. With the brushes 34 passing over segment 5, negative potential would be supplied from grounded battery 21, segment 16, segment 17, contactor 13, over conductor 38 to segment 5. Likewise, positive current would be supplied from grounded battery 19, conductor 22, armature 24 of polar 50 relay 25, which has been energized to its opposite position, conductor 39 to segment S of distributor ring 29. Each of the feeler contactors 8 to 12, inclusive, is connected over an individual conductor with an associate segment 0 (zero) to 4 of the transmitting distributor ring 39. Accordingly, 55 when a feeler lever encounters a perforated position in the tape, its contactor will be moved into one position, say the right-hand one (Fig. 1), engaging the contact block 15; while if said feeler lever encounters a nonperforated position, its contactor will assume an opposite condition; that 60 is, contacting the opposite block 17. The designation of positive or minus signals to correspond with perforated or non-perforated signal components is arbitrary, and is to be understood that the reverse association is equally practicable.
- 65 Not only is the foregoing true of the five feeler levers associated with contactors 8 to 12, inclusive, but also of the special feeler lever associated with contactors 13 and 14. In the case of the special or sixth feeler lever, however, when a perforation is sensed, and both contactors are moved 70

to the right, contactor 14 will be introducing negative current from battery source 21 to the winding of polar relay 25, while contactor 13 will be introducing positive battery from source 19 over conductor 38 to the stop segment 5. Conversely, with the contactors 13 and 14 in the opposite position, that is, engaging contact blocks 17 and 18, positive current originating from source 19 will be impressed through contactor 14 to the winding of bias polar relay 25, while negative current from source 21 will be introduced over conductor 38 to the stop segment 5. Accordingly, since armature 24 of relay 25 is connected to the start segment S, the result of the operation of the sixth or special feeler lever will be understood as one controlling the reversal of current for start segment S; that is to say, with a given condition on the part of segment 5 which may be either plus or minus, the sixth feeler lever controlling contactors 13 and 14 operates to provide an opposite current potential to the start segment S.

The purpose of having provided polar relay 25 with its armature 24 connecting plus or minus current to the segment S instead of directly connecting the contactor 14 to said segment S is to permit the start impulse signal interval to be stored. The transmitter utilized is of the well-known magnet type wherein a new signal is sensed during the start interval. If a new signal should be sensed which would cause the contactors 13 and 14 to move to their opposite position, the start impulse would be of the same polarity as the stop impulse. However, by providing the polar relay 25 the armature 24 thereof will be held in a position whereby potential opposite to that of the stop segment 5 will be assured, as the armature 24 retains such position until the brushes 34 have passed the start segment S, or until brushes 35 sweep across segment 26 of ring 27 thus providing a grounded circuit for the polar relay 25. At this time the armature 24 may move to the opposite side if the contactors 13 and 14 have moved, but the start impulse has already been transmitted.

In Fig. 1, the reference character 5 designates a receiving station and within said outline are contained the symbols representing important apparatus responsive to the signals generated by the transmitting distributor 28. However, intermediate the transmitting station 2 and the receiving station 5 is the repeating station 3 whereby the signals are repeated with renewed strength and form. The line wire 1 extending from the transmitting station is connected at the repeating station 3 to the polar relay 41 and then to ground. The armature 42 of relay 41 is connected over conductor 43 to the receiving relay 4 at the repeating station, and then through battery 44 to ground. Receiving magnet 4 controls, through mechanism hereinafter described, a pair of retransmitting contacts 45 and 46 connected to batteries 47 and 48 respectively. The retransmitting contacts 45 and 46 serve to connect the associated batteries 47 and 48 over conductor 6 to the polar relay 51 at the receiving station 5.

Magnet 4 has an armature 52 pivoted to a supporting frame by pivot 53. A retractile spring 54 attached to an arm 55 of lever 52 tends to bias lever 52 counterclockwise. Extension 55 constitutes a follower for a six-tooth cam 56 fixed to a cam sleeve 57 which is sleeved upon a continuously rotating power shaft 58. A retransmitting member 61 is pivoted to the frame by pivot 53 and terminates in a thin flat edge which cooperates with a locking bell crank lever 62. Member

61 is supported between arms 52 and 55 by compression springs 63 and 64. The member 61 is positioned positively by engagement between the thin edge of member 61 and a confronting thin edge of a locking bell crank lever 62 which is pivoted to the frame at 65 and is biased in a clockwise direction by a spring 66, and constitutes a follower for a seven-tooth cam 67 which is fixed with cam 56 upon cam sleeve 57. Carried on the retransmitting member 61 is a retransmitting tongue 68 which carries on its end, and insulated therefrom, contact members 71 and 72. Contact member 71 operates between the aforementioned contacts 45 and 46, in a manner to be hereinafter described, to control the retransmission of signal impulses from the repeating apparatus. Contact member 72 operates between a pair of contacts 73 and 74, as will presently appear.

Power shaft 58, besides carrying the cams 56 and 67 also carries a stop arm 75 which engages a gate 76 pivoted at 77 upon a member 78. Gate 76 is restrained by a latch 79 (Fig. 3) pivoted at 81 upon the member 78 and tensioned by a compression spring 82 extending from latch 79 to member 78. Extending between latch 79 and the armature 52 of magnet 4 is a start lever 83, pivoted to the frame at 84 and engaging at the end of its horizontal arm a plunger 85 slidable in frame part 86 and engaging at its upper end a projection on armature 52. Also mounted on shaft 58 is a cam 87, which cooperates with a follower of 88 integral with stop gate 76 to actuate said stop gate at the end of each revolution of shaft 58, so that said stop gate 76 will be invariably held on the stop position at the end of each signal, and the stop arm 75 will invariably engage said stop gate 76 regardless of the position of the armature 52 at that time. Also mounted on the shaft 58 is a cam 89 which is adapted to operate a set of contacts 91 and 92 in the stop position of the selector shaft 58. The cam 89 operates upon a contact tongue 93, in turn, to close the contact 91 or 92 to ground.

The operation of the regenerative repeater 3 will now be described. For the purposes of the present description it will be assumed that battery 19 of the transmitter 2 supplies marking current to the signal line conductor 1 and the battery 21 supplies spacing current thereto. The condition 50 of the system as shown in Fig. 1 is that of rest or idleness of the line with the contact 20 open and the magnet 31 de-energized so that armature 36 is released to hold the distributor arm 28 against rotation, thus maintaining brushes 34 in engagement with the No. 5 segment, which according to the present invention is substituted for the customarily independent stop segment which has been omitted and consequently merged into the No. 5 segment. It is thus seen that the 55 stop impulse will be of marking or spacing nature dependent upon the nature of the No. 5 impulse of the last transmitted code or combination. The arrangement as shown in Fig. 1 is such that the last transmitted impulse for the No. 5 interval is 60 of marking nature from battery 19 so that the current of marking nature is conducted over the line conductor 1 through the windings of the polar relay 41 of the regenerative repeater 41 at station 3. Thus the armature 42 of the polar relay 41 is held to the marking side (as shown), thus closing contact 95 thereof, and opening contact 96.

The operating shaft 58 of the repeater is shown with the cams thereon in the stop position, with the stop gate 76 acting to prevent the rotation

of said shaft by blocking the stop arm 75. In this position the cam 89 holds the armature 93 against the lower contact 92 and the member 61 is held in the position shown in Fig. 1 with the contact 73 closed, thereby completing an energizing circuit for the receiving magnet 4 of the repeater from battery 44, through the winding of magnet 4, over conductor 43, then through armature 42 and contact 95, over conductors 97 and 98, through contact 73, over contact tongue 72, over conductor 99, through contact 92 and over contact tongue 93 to ground.

Now, if the stop current on the line 1 is of spacing nature instead of marking nature as just described, then spacing current will be impressed on the line conductor 1 from battery 21 over the circuit previously described to energize the polar relay 41 in such a manner as to swing its armature 42 to close its contact 96 and open its contact 95. Then, as will presently appear, the arm 61 will have assumed the position on its spacing side, which is opposite to that shown in Fig. 1 so as to bring the contact tongue 72 into contact with lower contact 74, thus completing an energizing circuit for the receiving magnet from battery 44, through the winding of magnet 4, over conductor 43, through armature 42 and contact 96, over conductor 101, through contact 74, over contact tongue 72, over conductor 99, through contact 92, and then over contact tongue 93 to ground. As previously described, the contact 92 is closed only during the stop interval, and during the remaining signal impulse intervals contact 91 is closed, and contact 92 remains open, so that the energizing circuit for magnet 4 becomes independent of the contacts 73 and 74, as will presently appear.

Upon de-energization of magnet 4, armature 52 will be released, permitting the cam follower 55 to drop into the path of the six-tooth cam 56 and permitting the armature extension 52 to push the plunger 85, which will operate lever 83 to cause the operation, in turn, of latch 79 which will release the gate 76 to permit stop arm 75 to escape and thus permit the rotation of the cam sleeve 57 and the cams 56, 67, 87 and 89 thereon, by the power of shaft 58, through the instrumentality of a friction clutch (not shown). Operation of armature 52, when released by the de-energized magnet 4, also compresses spring 63 (since spring 54 is stronger than spring 63) and releases spring 64, but transmitting element 61 resists the spring pressure because it is still locked by locking lever 62, which is in the path of the seven-tooth cam 67, which cam now is starting to rotate. The first mechanical action of the cam sleeve 57 and its cams is to operate the lock lever 62 counterclockwise by cam 67, thereby releasing member 61, which moves tongue 71 from contact 45 to contact 46, and tongue 72 from contact 73 to contact 74. The movement of the contact tongue 71 from contact 45 to contact 46 causes the signal to be repeated from the transmitting station 2 to the receiving station 5, the repeated signal effecting the polar relay 51 in a manner to be hereinafter described. The operation of locking lever 62 is momentary because of the short arcuate dimension of the teeth of cam 67, and member 61 immediately is relocked. In operating to unlock the member 61, locking lever 62 permits no movement of member 61 while the flat side of its thin edge is in engagement with member 61, the release of member 61 being made suddenly at the instant when the end of

lever 62 leaves the end of member 61. The impulse from station 2, which now is repeated to station 5, thus has been determined in point of time solely by the movement of cam 67 acting through lever 62 to release member 61, but has been determined as to electrical nature, solely by the position of armature 52 which has been controlled solely by the signal received in magnet 4 under the control of station 2.

As the cam sleeve 57 begins to rotate, the projection of cam 89 fixed to said sleeve passes out of engagement with the contactor 93 so that said contactor will operate to open contact 92 and close contact 91. Contact 92 remains open and contact 91 remains closed, therefore, during the continuance of the entire cycle, except for a portion of the No. 5 impulse interval. Thus it will be noted that at the end of each cycle, commencing with the last portion of the No. 5 impulse interval, contact 92 will be closed and the magnet 4 may be energized either in response to marking or spacing signals, as previously described, over the circuits including contacts 95 and 96, and 74 and 73, respectively, for marking and spacing. However, during the remaining portion of the cycle when contact 91 is closed, the contacts 73 and 74 are ineffective, and the magnet 4 will respond only to marking impulses, the spacing impulses causing said magnet to become de-energized in the manner well known in the art.

Cam 87, as previously described, operates upon the follower arm 88 integral with the gate 76. In the stop position of the sleeve 57, the high portion of the cam 87 assumes the position shown in the Fig. 1, just having passed the projecting portion 88 so that upon the receipt of the start impulse, the magnet 4 will become de-energized and latch 79 will be disengaged from the gate 76, permitting the stop arm 75, under the influence of the friction clutch connection to shaft 58, to rotate the gate 76, the cam 87 not at this time preventing movement of the arm 88. However, near the end of the cycle of rotation of sleeve 57 the high portion on cam 87 cooperates with the arm 88 so as to rotate the stop gate 76 in a counterclockwise direction to bring the stop portion of the stop gate 76 into the path of the stop arm 75, regardless of the state of energization or de-energization of the magnet 4, thus invariably causing the stop arm 75 to engage the gate 76 for stop purposes, since as previously described the stop impulse may be of marking or spacing nature, corresponding to the nature of the No. 5 signal impulse of which it is a part.

Referring again to the cycle of events during the rotation of the cam sleeve 57, the next step following initiation of rotation is the engagement of a tooth of cam 56 with its follower arm 55, whereby armature 52 is moved toward or against its controlling magnet 4. This action occurs six times in each cycle, each such occurrence at about the middle of each of six of the code signal impulses; namely, zero, first, second, third, fourth, and fifth, intelligence signals (the fifth signal including also the stop signal of the code). In each instance, armature 52 will be held by the magnetism of energized magnet 4 if the instant signal, being a marking signal, operates to energize the magnet 4; but in each instance, armature 52 will be released by the passing of a tooth on the cam 56 by the follower arm 55 if the signal impulse is of spacing nature. In every such occurrence, actuation of follower 55 by cam 56, and the retention or release of armature 52 by magnet 4 will be followed imme-

diately by the operation of the lock lever 62 by cam 67, which will permit member 61 to operate the contact tongues 71 and 72 into engagement with their respective contacts depending upon whether the magnet 4 has retained armature 52 and has compressed spring 64, urging member 61 upwardly when unlocked by lever 62; or has released armature 52 and has compressed spring 63, urging member 61 downwardly when released by lever 62.

In prior structures, in each code group of impulses, a final impulse or a stop impulse is provided which is independent of the intelligence code impulse and is always of marking characteristics, thereby attracting the armature 52. However, in accordance with the present invention, the independent stop interval has been omitted and has been incorporated in the No. 5 code signal interval, said No. 5 impulse functioning dually as a signaling impulse and a stop impulse. During the time said No. 5 impulse functions as a stop impulse, the cam 89 acts on the contact tongue 93 to close the contact 92 to render the magnet 4 responsive to signals of either marking or spacing nature, depending upon the nature of the No. 5 impulse interval. The contact 92 is closed only after the fifth impulse has performed its selecting function. From the foregoing, then, it will be noted that if contact 92 is closed, the magnet 4 will be energized whether the No. 5 signal impulse was marking or spacing. The contact 92 is closed only during the interval that the fifth impulse functions as a stop impulse, because the complementary interval of said impulse is utilized for signaling purposes. Thus a portion of the fifth impulse is utilized for stop purposes only, in lieu of the usual independent stop interval.

In the description of operation of the transmitting and repeating stations it is assumed, of course, that the distributor arm 28 rotates in synchronism with the cam sleeve 57. It will be further assumed that the brushes 34, are just entering upon contactual engagement with the No. 5 impulse segment. Accordingly since the cam sleeve 57 is in synchronism with the transmitting distributor, the high portion of cam 89 is approaching the contact tongue 93 which now is in contactual engagement with contact 91. In this condition of the circuit and apparatus, if the fifth signal impulse is marking, then the contact tongue 42 of polar relay 41 will be biased so as to close contact 95, and the energizing circuit for magnet 4 will be closed over the following circuit: From battery 44, through the winding of magnet 4, over conductor 43, and over contact tongue 42, through contact 95, over conductors 97 and 102, through contact 91 and over contact tongue 93 to ground. It will be noted that, in response to a marking signal the armature 52 will be attracted, and the member 61 will be operated to the marking side, which will close contacts 45 and 73. Now, since the No. 5 impulse is marking as the cam 89 reaches the contact tongue 93 and operates said tongue to close contact 92, the magnet 4 will still remain energized, but over the circuit extending from battery 44, through the winding of magnet 4, over conductor 43, through contact tongue 42, through contact 95, over conductors 97 and 98, through contact 73, over tongue 72 and over conductor 99, through contact 92 and over contact tongue 93 to ground.

On the other hand, let it be assumed that the No. 5 signal impulse is of spacing nature and, as-

sume again that the cam 89 is in a position where its projection has not yet reached the contact tongue 93 during the No. 5 impulse interval. Then contact 91 will be closed, but the contact tongue 42 of polar relay 41 will be in engagement with the spacing contact 96, whereupon the magnet 4 will become de-energized since the energizing circuit therefore has been broken at contact 92. In response to the spacing signal, however, the magnet 4 becomes de-energized and the armature 52 is released, thus the member 61 will assume its spacing position, as previously described, to close contacts 46 and 74. Then, when the high portion of cam 89 cooperates with the contact tongue 93 to close contact 92, the magnet 4 will become energized over a circuit extending from battery 44, through the winding of magnet 4, over conductor 43, through contact tongue 42 and contact 96, over conductor 101, through contact 74 over contact tongue 72, over conductor 99, through contact 92 and over contact tongue 93 to ground. It is thus seen that the magnet 4 will become energized during the time interval that the No. 5 impulse functions as a stop impulse regardless of whether the impulse is of marking or spacing nature.

From the previous description it will be noted that the impulse following the No. 5 impulse, which is the start impulse, is always of an electrical characteristic or nature opposite to the nature or characteristic of the No. 5 impulse so as to cause the de-energization of the receiving magnet, either by spacing or marking current. In the prior structure the marking current designated the stop interval, and the start interval was always of a spacing nature. In accordance with the present invention, wherein the nature of the start current is determined by the nature of the current of the No. 5 impulse, it is seen that the stopping current may be of either nature, and hence the starting current must be the reverse nature. It will be noted that regardless of whether the magnet 4 has been energized in the previous code cycle by a marking or spacing signal, the start signal impulse being of opposite nature will cause the armature 42 of polar relay 41 to swing to the opposite contact, thus breaking the previous energizing circuit for the magnet 4, as previously described, thereby causing the magnet 4 to become de-energized and the cam sleeve 57 to rotate by the operation of plunger 85 by armature 52, and consequently the operation of the retransmitting contacts 45 and 46 to effect the repetition of the signals and transmission thereof over line 6.

As previously mentioned, the reference character 5 indicates a receiving station having receiving apparatus of the type disclosed in co-pending application Serial No. 334,108, and which, for the purposes of the present disclosure, will be briefly described. The reference character 51 indicates a polar relay having an armature 105 which reciprocates between two contact points 106 and 107 which are part of a local circuit for controlling the operation of the receiving magnet 108. Also located in the receiving station 5 are a pair of contactors indicated 109 and 111. Contactor 109 reciprocates between a pair of contact points 112 and 113, and the contactor 111 operates between a pair of contact points 114 and 115. Contactor 109 is operated by a special cam carried on the selector cam sleeve of a printer of the type shown in U. S. Patent No. 2,247,408, issued July 1, 1941, to A. H. Reiher, and this cam is analogous to cam 89 of the regenerative repeat-

er mechanism at the repeating station 3. Thus, contactor 109 and its associated contacts 112 and 113 correspond in function to contactor 93 and contacts 91 and 92, respectively, of the repeating mechanism. Also, contactor 105 and its associated contacts 106 and 107, correspond with and are analogous to contact tongues 72 and 74, respectively.

Briefly stated, armature 105 of relay 51 fluctuates in accordance with the signal impulses transmitted over the line 6 from the repeating station 3, and contactor 109, being controlled by a cam apex on the selector cam sleeve, rests against contact point 112 at all times except during the stop and start signal interval. Also, contactor 111 being controlled by the No. 5 signal is moved into one or the other of two alternative positions as a result of the operation of the transfer mechanism only during the period corresponding to this impulse. More specifically, the contactor 109 rests against the contact 113 only during the latter portion of the No. 5 impulse interval in the manner as similarly described in the case of the repeating mechanism shown in the repeating station 3. Under an assumed set of conditions, for example, in response to marking signals, both contactors 105 and 111 will be deflected so as to engage their contact points 106 and 114 respectively, while in response to spacing signal impulses, said armatures or contactors 105 and 111 will be in their opposite position, that is, engaging respectively their contact points 107 and 115. Also, it is to be recalled that since the No. 5 impulse functions in the dual capacity of effecting the distributor stop control as well as entering into the permutation code, each signal must be considered with reference to the No. 5 impulse of the preceding signal which affects the current characteristics of the start impulse as well as of the concluding No. 5 impulse, because it, together with impulses Nos. 1, 2, 3, and 4, comprises the code combination of the particular signal.

Accordingly, when the No. 5 impulse of a preceding signal happens to be marking, armature 105 will be thrust into engagement with its contact point 106, contactor 109 will be permitted to engage its contact point 112 (on account of the operation of the cam on the selector sleeve), and contactor 111, as a result of a transfer operation, as clearly described in the aforementioned patent, will be moved into engagement with its contact point 114. This will complete a circuit traceable from grounded battery 116 through the winding of magnet 108, over contactor 111, through contact 114 (with which it is now in engagement), conductor 117, contact 106, and contactor 105 to ground. As a result of the continued energization of magnet 108 its armature is held, and the rotation of the selector cam sleeve is arrested in accordance with the conventional operation of printing telegraph selector shafts. This condition continues until the circuit for energizing the magnet 108 is broken, which change occurs upon the receipt of a proper start impulse over segment S of the transmitter 2 and repeated over the contact 46 or 45 of the repeater 3. The polarity of the start signal being opposite to that of the No. 5 or stop signal impulse, as already explained, causes armature 105 of polar magnet 51 to be moved to engage its contact point 107 and away from its contact point 106. This interrupts or opens the circuit for magnet 108, causing the release of its armature and consequently initiates the rotation of the receiving distributor cam sleeve shaft in a

manner clearly described in the Reiber Patent 2,247,408.

As the distributor shaft or cam sleeve of the printer mechanism, indicated at the receiving station 5, rotates, the cam apex controlling the contactor 109, rides off the contactor 109 permitting contactor 109 to be drawn away from its contact point 113 and to come into engagement instead with its contact point 112. Meanwhile contactor 111 remains in engagement with its contact point 114 because it can be changed only during the fifth impulse interval. As a result of the change in contactor 109 from contact point 113 to contact point 112, no effect is obtained at this time, because magnet 108 continues to be de-energized until, during the course of the six signal impulse intervals, 0, 1, 2, 3, 4 and 5, and armature 105 in response to its relay 51 returns to engage its contact point 106, which response can occur only under the control of marking signal impulses. If the signal impulse corresponding to the No. 5 interval is of spacing nature, then contactor 105 will be swung over to the contact 107 and thereby open contact 106. As a result of this selection, contactor 111 will engage its upper contact point 115 instead of the lower contact point 114, while (because of the cam apex on the special cam previously mentioned) contactor 109 will again be operated against contact point 113. Thus, a circuit will be completed for energizing the magnet 108 extending from grounded battery 116, through the winding of magnet 108, over contactor 111, through contact 115, over conductor 118, over contactor 109, through contact 113, over conductor 119, through contact 107, and over contactor 105 to ground.

As a result, magnet 108 is held energized, which is the proper condition corresponding to a stop impulse, until an opposite current condition is received by the relay 51, causing its armature 105 to be withdrawn from contact point 107 and to engage instead the contact point 106. When this occurs, contactor 109 is still held against its contact 113 because of the function of the special cam on the selector sleeve (which is analogous to the function of cam 89 of the repeating station 3 upon the contactor 93), which maintains said condition during the interval corresponding to the start impulse. Meanwhile, the last described movement of armature 105 causes the energizing circuit for magnet 108 to be broken, and accordingly releasing its armature for the purpose of initiating rotation of the receiving selector cam sleeve or shaft as previously described. Thereafter, and coincident with the 0 (zero) signal interval, contactor 109 is restored to its condition which prevailed during the longest portion of the cycle; that is, engaging its contact 112. When this occurs, that is, when armature 105 of relay 51 engages contact point 106, marking impulses are thereafter interpreted as magnet 108 energizing impulses, because contactor 111 continues in engagement with its contact point 115, causing the magnet 108 energizing circuit to be completed over the following described circuit: From grounded battery 116, through the winding of magnet 108, contactor 111, contact 115, conductor 118, contactor 109, contact 112, conductors 121 and 117, contact 106, contactor 105 to ground. Thus, phasing of the receiving magnet 108 as well as its controlled distributor or selector shaft is regulated, notwithstanding the reversed conditions of the No. 5 and start impulses.

From the foregoing description it is observed that a regenerative repeater has been provided

for a system of telegraph communication which embodies a special form of signalling wherein the normal stop impulse interval has been eliminated and wherein the final impulse of the signal code is utilized in a dual capacity to serve for signalling purposes as well as phasing purposes, and wherein the start impulse functions for starting purposes irrespective of the nature of the signal characteristic, that is, whether it is marking or spacing, the only requisite being that the start impulse is of a nature opposite to that of the final No. 5 code signal impulse interval. It is further noted that, although in Fig. 2 the fifth impulse interval is indicated as being somewhat longer than the other impulse intervals, it is to be understood that such relation is not essential to the successful operation of the arrangement disclosed herein, but is merely so shown since in existing start-stop signalling systems the normal stop period or interval is slightly longer than the remaining impulse intervals.

While the arrangement disclosed in the drawing has been explained and described with reference to specific embodiments, it is not intended to be restricted in any manner to the language of the detailed specification nor to the illustrations in the accompanying drawing, except as indicated in the hereunto appended claims.

What is claimed is:

1. In a telegraph repeater, a magnet responsive to current impulses for releasing a timing cam sleeve for rotation, a contact member for retransmitting a received signal, an armature controlled by a received signal, a spring tensioned by said armature and acting to urge said contact member to an alternative position, a locking member restraining said contact member, said timing cam sleeve operating said locking member to release said contact member to control the timing of a retransmitted signal, a receiving line relay having an armature responsive to alternative line current conditions, two electrical circuits including said line relay armature and said magnet, a principal switch effective in response to the final impulse of a series of impulses comprising a signal to prepare one or the other of said two circuits to said magnet, and a shunting switch effective during certain other intervals only of said series of impulses for shunting one of said circuits.

2. In a telegraphic repeating device, a contact member for retransmitting a received signal, an armature controlled by a received signal, a spring tensioned by said armature and acting to urge said contact member to an alternative position, a locking member restraining said contact member, a timing cam operating said locking member to release said contact member to control timing of a retransmitted signal, a receiving line relay having an armature responsive to alternative line current conditions, two electrical circuits including said line relay armature and said magnet, a principal switch responsive to the final impulse of a series of impulses comprising a signal to prepare one or the other of said two circuits to said magnet, and a shunting switch effective during certain other intervals only of said series of impulses for shunting one of said circuits.

3. In a telegraph repeating apparatus, a signal controlled magnet, a line relay having an armature responsive alternatively in accordance with two different received line signal impulse conditions, a pair of electrical circuits communicable with said line relay armature for establishing connection with said receiving magnet, a con-

tactor effective in accordance with the response of said magnet to said line signal impulse conditions for selecting one or the other of said two circuits, means for timing the operation of said contactor, and means effective during an initial period of each signal for shunting one of said circuits to render said magnet normally responsive to only one of said line signal conditions, said means effective during a final period of each signal to render said magnet responsive to either line signal condition, whereby said magnet will invariably be rendered unenergized in response to the next contiguous impulse irrespective of its line condition.

4. In a telegraph repeating apparatus, a signal controlled magnet, an armature for said magnet, retransmitting contacts, centralized means associated with said armature and responsive thereto for operating said contacts to effect the regeneration of repeated signals, means for assisting said armature, means for timing the response of said centralized means to the movements of said armature, a polar line relay responsive to alternative line current conditions, said relay having an armature, two electrical circuits connecting said line relay armature with said magnet, a principal switch carried by said centralized means responsive to the final impulse of a series of impulses comprising a signal for preparing one of said two circuit paths to said magnet, and a shunting switch effective during certain other intervals only of said series of impulses for shunting one of said circuits.

5. In a telegraph repeating apparatus, a signal controlled magnet, an armature for said magnet, retransmitting contacts, centralized means associated with said armature and responsive thereto for operating said contacts to effect the regeneration of repeated signals, a cam assembly, a cam in said assembly effective for assisting said armature, a further cam in said assembly for timing the response of said centralized means to the movements of said armature, a line relay responsive to alternative line current conditions, said relay having an armature, two electrical circuits connecting said line relay armature with said magnet, a principal switch carried by said centralized means for selectively preparing said circuit paths to said magnet, and a shunting switch controlled by a cam in said assembly effective during certain signaling intervals for shunting one of said circuits.

6. In a regenerative repeater, signal timing means quiescent during non-signalling periods, means to initiate said means into operation at the beginning of each signal, a magnet to control the initiating means, a plurality of energizing circuits for said magnet, a principal switch for selectively preparing said circuit paths to said magnet, and a shunting switch controlled by said signal timing means effective during certain signalling intervals for shunting one of said circuits.

7. In a telegraph system, means to transmit equal length permutation start-stop code signals, timing cams started into rotation at the beginning of each signal, signal retransmitting means timed in operation by said timing cams, means governed by said timing cams to control the spacing or marking nature of each element of the signal by the nature of the corresponding element of said original signals, means to stop the motion of the timing cams at the end of a signal independent of the nature of the line current, and means controlled by certain of said cams to

restart said timing cams only when the nature of the line current changes.

8. In a regenerative repeater, a line relay responsive to incoming signals, means to simultaneously generate two sets of signals under control of said line relay comprising a plurality of pairs of contacts, contact operating means therefor, and signal controlled means for controlling the operation of said contact operating means, and means comprising a shunting switch also controlled by said signal controlled means to invert some only of the elements in one of the sets of signals.

9. In a regenerative repeater, a line relay responsive to incoming signals, means to simultaneously generate two sets of permutation code signals under control of said line relay comprising a plurality of pairs of contacts, contact operating means therefor, and signal controlled means for controlling the operation of said contact operating means whereby at least one of the elements of one of said sets of signals is adapted to control dual functions, and means comprising a shunting switch also controlled by said signal controlled means for causing said element to control phasing operations of the repeater.

10. In a regenerative repeater, signal timing cams quiescent during non-signalling periods, means to initiate said cams into operation at the beginning of each signal, each of said signals comprising at least one element having dual func-

tionary characteristics, a magnet to control the initiating means, a plurality of energizing circuits for said magnet, and switching means controlled by certain of said cams to determine the energizing circuit for said magnet.

11. In a telegraph system, means to transmit equal length permutation start-stop code signals, each signal comprising at least one impulse element having dual functionality characteristics, a cam means started into operation at the beginning of each signal, signal retransmitting means timed in operation by said cam means, means comprising a shunting switch controlled by said cam means to control the functionality characteristics of said element, means to stop the motion of the cam means at the end of a signal independent of the characteristic of said element, and means controlled by said switch to restart the cam means only when the characteristic of the line current changes.

12. In a regenerative repeater, a timing instrumentality, means acting at the beginning of each received signal to start the timing instrumentality into operation, means controlled by the last impulse of a signal to determine the character of the corresponding impulse in the regenerated signal, a shunting switch, and means acting on said switch subsequently to said determining means to condition the starting means regardless of the character of the last impulse of the signal received.

LOUIS M. POTTS.
